UNITED STATES PATENT OFFICE

JOSEPH GOULDBOURN, FRED RICKS, AND WILLIAM RODERICK BARCLAY, OF LEICESTER, ENGLAND, ASSIGNEES TO UNITED SHOE MACHINERY CORPORATION, OF PATERSON, NEW JERSEY, A CORPORATION OF NEW JERSEY

HEEL-SEAT FITTING MACHINE

Application filed September 24, 1928, Serial No. 307,937, and in Great Britain October 1, 1927.

This invention relates to machines for use in the manufacture of shoes and is illustrated herein as embodied in a heel-seat fitting machine.

5 In the manufacture of women's shoes having wood heels, for example, surplus material is trimmed from the heel-seat portion of a sole attached to a shoe in order to provide a seat which will receive the cupped or concave 10 portion of the attaching face of the heel and to insure that the rim of the attaching face of the heel will bear snugly against the overlusted margin of the counter portion of the shoe upper.

15 Good shoemaking requires that a wood heel shall be firmly secured to the heel-seat portion of the shoe and that the margin of the sole shall be completely concealed by the engagement of the rim of the attaching face of the 20 heel against the shoe upper. Moreover, the junction of the sole and heel at the heel-breast line must be inconspicuous and the union of the parts must be smooth and neat in appearance.

25 In trimming the heel portion of the sole for the reception of a wood heel it is the usual practice to reduce the width of the sole rearwardly of the heel-breast line and to form shoulders substantially at the heel-breast line 30 of the sole against which shoulders the breast of the heel abuts. This operation is preferably performed after the sole is attached to the shoe upper, the sole-attaching stitching preferably extending a short distance rearwardly of the heel-breast line of the sole, leaving the rear portion of the sole loose from the shoe upper.

35 In carrying out the heel-seat fitting operation in machines of the drag-knife type 40 it is customary to distort the sole so that its marginal portions are curled away from the shoe upper, the drag-knife severing the curled marginal portions as it trims and bevels the sole. A heel-seat fitted by the distortion method generally has its marginal portions beveled at a relatively slight inclination to the heel-attaching surface of the sole. In some types of shoes, however, the sides of the cupped attaching faces of the 45 heels to be secured to the shoes are inclined

at steep angles to the bottoms of the attaching faces. In order to form heel seats shaped to receive heels such as are just described, it is desirable considerably to distort the rear portion of the sole.

55 When the sole is greatly distorted during the trimming operation the stitches attaching the sole to the shoe upper are often strained and weakened, or even pulled out, in the vicinity of the heel-breast line so that the 60 sole is in danger of pulling loose from the shoe upper at the heel-breast line. This permits heel-breast receiving shoulders which are formed at the breast line to sag or gap away from the shoe upper after the shoe has 65 been worn a short time.

70 It is an object of the invention to provide a machine of the drag-knife type for fitting heel-seat portions of soles while the soles are in an undistorted condition.

75 A further object of the invention is to provide a heel-seat fitting machine of the drag-knife type for trimming the heel-seat portions of soles which already have been attached to shoes without cutting the stitching 80 between the soles and the shoe uppers rearwardly of the breast line and without loosening the stitching in the vicinity of the heel-breast line.

85 With these objects in view a feature of the invention as embodied in the illustrated machine comprises the combination of a shoe support, crease plates or jaws constructed and arranged to enter the rand crease of a shoe on the support, and beveling knives for trimming the marginal portions of the sole of the shoe lengthwise of the shoe to reduce the heel seat portion thereof to fit the attaching face of a wood heel, said knives being inclined transversely of the heel-attaching surface of 90 the sole. An advantage of this feature is that beveling knives of different inclinations transversely of the heel-attaching face of the sole may be used in the machine to form complementary surfaces on said heel-attaching faces of soles for receiving cupped heel-attaching faces of heels having varying shapes.

95 In order to sever from the sole the marginal portions of the rear portion of the sole remaining attached to the sole after the oper- 100

ation of the beveling knives and at the same time to form heel-breast-receiving shoulders upon the sole, the machine, in accordance with a further feature of the invention, is 5 provided with the above-mentioned jaws for supporting the lateral portions of the rear portion of the sole, one of the jaws being movable toward and away from another jaw, and a cutter movable with the movable jaw and 10 also movable relatively to said jaw and constructed and arranged to form a heel-breast-receiving shoulder upon the sole while the sole is undistorted. The shouldering knives are mounted for rectilinear movement trans- 15 versely of the sole of the shoe, said knives being inclined to the attaching surface of the sole transversely of the sole substantially at the same inclination as the beveling knives to form shoulders substantially at the heel-breast line of the sole. The shoulder-forming knives of the illustrated machine are sprung against the forward edges of the crease plates and when inclined to the crease plates as 20 illustrated cooperated with the forward edges of the crease plates to constitute shear couples which form heel-breast-receiving shoulders upon the sole.

In accordance with another feature of the invention the illustrated machine is provided 30 with a pair of sliding beds for carrying the beveling knives and the shouldering knives as well as the crease plates, the sliding beds being constructed and arranged to move toward and away from one another, and the 35 beveling and shouldering knives also being mounted for relative movement with the sliding beds and the crease plates.

Another feature of the invention as embodied in the illustrated machine is a crease 40 plate provided with a thin finger portion constructed to enter the rand crease of a shoe without distorting the sole of the shoe, said crease plate also having in its sole-engaging surface a guideway in which one of the beveling knives is arranged for movement.

A further feature of the invention includes 50 a novel shoe-positioning construction including a back gage which is regulated by a device for engaging a heel similar to the heel which is to be placed upon the shoe to be operated on, the back gage being constructed and arranged to position the shoe lengthwise in the machine by contact with the rear portion of the shoe upper. The heel engaging device is set by the heel and comprises abutments adapted to engage the opposite sides of the heel to position the same widthwise, and members to engage the rear and the breast of the heel to position the heel lengthwise, the abutments being constructed and arranged to centralize the heel widthwise prior to the lengthwise positioning of the heel by the abutments. The heel-engaging device and the back gage are illustrated 60 herein as provided with means for urging

the heel-engaging device against the heel and the back gage against the rear portion of the upper of the shoe and as also provided with means for locking the heel in position in the heel-engaging device and for locking the 70 back gage against rearward movement when it is engaged by the shoe upper.

The machine illustrated as embodying the invention will be described with reference to the drawings, in which

Fig. 1 is a side elevational view of a heel-seat fitting machine embodying the invention, some parts being shown in section more clearly to bring out the construction thereof;

Fig. 2 is a plan view of the machine with parts broken away to show the interior structure thereof;

Fig. 3 is a front view of the machine with parts shown in section;

Fig. 4 is a detail sectional view of a portion 85 of the machine, showing a shoe in position therein to have its sole trimmed to form a heel-seat for a heel;

Fig. 5 is a perspective view of the rear portion of a shoe during performance of the 90 heel-seat fitting operation, showing the position of the crease plates of the machine and the beveling knives for trimming the marginal portions of the heel-seat lengthwise of 95 the sole relatively to the shoe;

Fig. 6 is a section taken on the line VI—VI of Fig. 4;

Fig. 7 is a sectional view somewhat similar to Fig. 6 but illustrating the shoe to be operated upon as mounted on a last and showing modified types of crease plates which 100 co-operate with the last for positioning the shoe;

Fig. 8 is a perspective view showing in detail the construction of the beveling knives and knife actuating mechanism for trimming the marginal portions of the heel portion of the sole lengthwise of the sole;

Fig. 9 is a front view partly in section of mechanism for assisting in positioning and locking a floating back gage and a heel-receiving gage;

Fig. 10 is a side elevational view of the mechanism shown in Fig. 9 with parts broken away to show the interior construction 110 thereof;

Fig. 11 is a perspective view of the rear portion of an inverted shoe the heel-seat portion of which has been fitted by the above illustrated machine for the reception of a 120 wood heel;

Fig. 12 is a perspective view of the rear portion of an inverted shoe illustrating a modified form of heel-seat part of the fitting of which has been done by the machine 125 shown in the foregoing figures; and

Fig. 13 is a perspective view of a modified form of crease plate.

For purposes of illustration it will be assumed that the shoe being operated upon is 130 of the well-known McKay type and that said

shoe is to have its heel-seat trimmed for the reception of a Cuban heel. The shoe shown in Fig. 11 has its sole-attaching seam A extending along the shank portion B of the shoe to points somewhat rearward of the breast line C of the sole of the shoe. The heel-seat portion of the sole F of the shoe may be loose rearwardly of the ends of the stitching or it may be held by a central tack D. The rear portion E of the sole F terminates a considerable distance from the rear of the shoe and is what is often termed a "short sole."

The heel-seat portion G of the sole F of the illustrated shoe is trimmed along its marginal portions lengthwise of the sole of the shoe after the sole has been attached to the shoe to form steep bevels H which may, if desired, be of such a steep inclination relative to the heel-attaching face W of the heel-seat portion of the sole of the shoe as not to pierce the line of stitches A rearwardly of the heel-breast line C. The heel-seat is also trimmed to form a pair of heel-breast receiving shoulders K extending laterally of the sole at its heel-breast line.

The rear portion of the heel-seat of the sole illustrated in Fig. 12 has been given a preliminary trimming prior to its application to the shoe upper, the margin O to the rear of lines P being trimmed to form a U-shaped portion Q somewhat longer than the parallel-sided portion N of the sole of the shoe shown in Fig. 11. The heel-seat portion of the sole illustrated in Fig. 12 is, from the lines P forwardly, of the same form as the heel-seat portion of the shoe illustrated in Fig. 11.

The illustrated machine, which will later be described in detail, comprises a support for holding the shoe to be trimmed, which shoe is supported with its sole uppermost and its heel away from the operator, mechanism for arranging the shoe in proper position in the machine so that the trimming operation may be performed, a pair of knives which form the bevels H on the heel-seat portion G of the sole of a shoe and a pair of knives for forming the heel-breast receiving shoulders K.

The machine as a whole includes three principal groups of instrumentalities carried by a lower head 2, a middle head 4 and a top head 6, respectively. The lower head 2 carries the shoe-supporting means and forms a base for the middle head 4 and the top head 6. The middle head 4 carries sole-trimming mechanism and the mechanism therefor while the upper head 6 carries heel-gaging mechanism by which the position of the shoulders K is determined.

The lower head 2 carries a forwardly extending horizontal bracket 8 having a T-shaped horizontal guideway 10 extending forwardly and rearwardly of the machine.

Slidably mounted in the guideway 10 is a work support or jack 12 (Fig. 1) having a T-shaped base 14 (Fig. 3) slidably mounted in the guideway 10 so that a shoe mounted thereon may be moved into and out of trimming position. The work support also comprises a vertically extending portion 16 bored as shown at 18 to receive a post 20 having a slot 22 extending in the direction of its length and containing a pin 24 which is supported by the vertically extending portion 16 of the work support. The upper end of the post 20 is provided with a threaded recess 26 which receives the threaded shank portion 28 of a shoe-supporting plate 30 (Figs. 1 and 4) fixed in adjusted position relatively to the post 20 by a nut 32 upon the shank portion of the shoe-supporting plate 30. A spring 34 is located within the recess 26 of the post 20, the ends of which spring engage against the pin 24 and the lower end 36 of the shank 26 of the shoe-supporting plate 30, normally to hold the post 20 in the raised position shown in Fig. 1.

As will later be brought out, when the sole of the shoe is being trimmed the post 20 is in lowered position relatively to the vertically extending portion of the work support 16, as shown in Fig. 4. In order to hold the post 20 in raised position while the shoe is being trimmed, an arm 38 (Figs. 1 and 4) pivoted for movement about a pin 40 mounted in the forwardly extending horizontal bracket 8 is raised upwardly through a slot 42 (Fig. 2) in the bracket 8 and a slot 44 in the work support 16 into contact with the lower end 46 of the post 20. The forward end of the arm 38 is normally held downward by a heavy spring 48 which is connected to the arm at its forward portion 50. Pivoted about the pin 40 is also a forwardly extending dog 52 which is carried with but movable relatively to the arm 38 by a spring 54, the dog being adapted to engage a rack 56 at the under part of the work support 12 to hold the work support from sliding forward when the shoe is having its heel-seat trimmed.

The rear portion 58 of the arm 38 is connected by a link 60 to one end of a floating lever 62 the other end of which is pivoted to a plunger 64 which through associated mechanism hereinafter described operates a pair of crease plates or jaws 66 which are arranged to enter the rand crease of the shoe to be operated on as far as the line of stitching A between the shoe upper and the sole. The floating lever 62 is connected at its central portion to a rod 68 (Fig. 1), which extends downwardly to a treadle 72.

The middle head 4 is provided with bearings one of which is shown at 74 (Figs. 1 and 3) for supporting a forwardly and rearwardly extending driving shaft 76. A cam 78 having cam grooves 80, 82 is mounted upon the shaft 76 to actuate through other mecha-

nism which will later be described beveling knives or blades 84 which are moved lengthwise of the sole to trim the marginal portions H of the heel-seat portion of the sole as well as shoulder knives or blades 86 which are moved transversely of the sole to form heel-breast receiving shoulders K.

The middle head 4 has on each side thereof and extending laterally therefrom a pair of brackets 88 (Fig. 2) spaced from one another, each pair providing a guideway 90 extending parallel to the front of the machine and slidably supporting and guiding two laterally movable sliding beds 92, the guideways on opposite sides of the machine being in the same horizontal plane and in line with one another.

Since the sliding beds 92 with their associated parts are the same on both sides of the machine, it will be necessary to describe but one side, it being understood that the side opposite that described has a reversed but corresponding part. Each of the sliding beds 92 carries one of the shoulder knives 86, one of the beveling knives 84 and one of the crease plates 66, and upon the under side of each of said sliding beds there is a boss 94 in which is fixed a depending stub 96 (Fig. 3) the lower end of which is pivoted at 98 to the outer end of a link 100, the other end of the two links being connected at 102 to the plunger 64 which is mounted for vertical movement in a bearing 104 in the lower head 2 of the machine. The lower end of the plunger 64 is connected to the floating lever 62 already described, the mechanism being constructed and arranged so that downward pull on the plunger rod will move the sliding beds 92 toward one another in the guideways 90 in the middle head 4 of the machine.

The lower end of the plunger rod 64 has a lug 106 (Fig. 1) extending forwardly therefrom, which lug is provided with a hook 108 to receive the end of a spring 110 the other end of which spring is connected to the lower head 2, the spring serving to keep the plunger rod 64 in a raised position which results in holding the sliding beds 92 at their extreme positions away from one another in the guideways 90.

The illustrated machine is also provided with a hold-down clamp 112 which serves to engage the heel-attaching face of the sole of the shoe between the beveling knives 84 (Fig. 5) while the sole is being trimmed in order to assist in tightly securing the sole against movement during the trimming operation. The hold-down clamp is pivoted at 114 (Fig. 1) to the top head 6 through an arm 116 which is connected near its central portion 118 to a downwardly extending clamp-actuating rod 120 which passes through the forwardly extending lug 106 on the plunger rod 64. The clamp-actuating rod 120 is provided with a

pair of collars 122, 124 the former of which serves to confine a spring 126 between itself and the forwardly extending lug 106 and the latter of which is adapted to be engaged by the lug 106 when the plunger rod is lowered. As the plunger 64 is lowered to draw the sliding beds 92 and their crease plates 66 together it will depress the rod 120 and cause the hold-down clamp 112 to engage the bottom of the sole of a shoe as shown in Fig. 4. A turn buckle 128 upon the rod 120 may be used for varying the amount of pressure with which the clamp will engage the sole of the shoe and the time at which such engagement will occur.

The crease plates 66, which are located at the forward inner corners of the sliding beds 92 and which assist in maintaining the sole in position to be trimmed just above their level (Fig. 4), are strong enough to resist the upward pressure of the work support 20 and include thin finger portions 130 (Fig. 8) adapted to enter between the shoe upper and the sole at the side of the heel-seat of the shoe. The upper surfaces of the crease plates 66 are provided with knife guideways 132 for receiving the beveling knives 84, said guideways being formed by the shoulders 134 extending lengthwise of the plates and the flat surface portions 136 which also extend lengthwise of the plates and serve to cut away part of the thickness of the crease plates to provide the fingered portions 130. The beveling knives 84 are adapted to move in the guideways along the angled portions 138 formed by the shoulders 134 and the flat surface portions 136, as shown in Fig. 8. The sliding beds 92 may be attached to the crease plates or jaws 66 in any convenient manner such as that shown in Figs. 3 and 8 in which each plate includes a tongued portion 140 and two threaded bolts 142 which may be fastened to the inner side 144 (Fig. 3) of the sliding beds 92. Although the crease plates or jaws and the sliding beds have been illustrated as separate parts, it will be understood that each sliding bed which supports one of the knives 84 and one of the shoulder forming knives 86 is rigidly attached to one of the crease plates and is, in effect, a part thereof.

Each sliding bed 92 is provided near its front margin with a laterally extending horizontal guideway 146 (Fig. 2). A knife carrier slide 148 is mounted for reciprocation in each guideway 146 and has fixed to it a downwardly extending rod 149 (Fig. 3) which is adjustable lengthwise of the slide in a slot 150 (Fig. 2) by means of a nut 152 threaded upon the upper portion 154 of the rod so that the initial position of the slide 148 in its guideway 146 may be adjusted, the downwardly extending rod 149 retaining a fixed position with respect to the

knife carrier slide 148 during the operation of the machine.

The lower portion of each downwardly extending rod 149 passes through a bifurcated portion 156 (Fig. 2) of an arm 158 which has a sleeve portion 160 mounted for turning movement upon the depending stub shaft 96 attached to the sliding bed 92. Mounted on each sleeve 160 is another arm 162 extending laterally of the machine, the end of which is pivoted to a link 164 extending rearwardly of the machine and pivoted to a cross-head 166 (Fig. 1) which is attached to a slider 168 adapted to slide forwardly and rearwardly 15 of the machine in a guideway 170 in the frame of the machine, the slider 168 carrying an upwardly extending roller 172 positioned in the cam groove 80 of the cam 78.

It will be clear that as the cam 78 is rotated and the cross-head 166 moved forwardly and rearwardly of the machine the knife carrier slides 148 will be moved laterally of the machine on the sliding bed 92. Since the connecting link 164 is of considerable length, 25 movement of the sliding beds toward and away from one another does not affect, to any harmful extent, the position of the knife carrier slide 148 relatively to the sliding bed 92.

30 The knife carrier slides 148 are each provided with an upwardly extending lug 174 having a cylindrical recess 176 (Fig. 3) with its axis parallel with the direction of movement of the knife-carrying slides 148. A 35 knife carrier 178 has a cylindrical shank portion 180 received by the cylindrical recessed portion 176 of each upwardly extending lug 174 and is held in place therein by a bolt 182 passing through the cylindrical bored portion. The knife carrier 178 is also provided with a portion 184 which extends forwardly of the machine and toward the center of the machine and includes a T-shaped groove 186 which receives the thin flat knife blade 86 and 40 a clamping piece 190 T-shaped in cross-section which is inserted in the T-shaped groove forward of the knife 86, the knife being held in position in the knife carrier by a screw 192 passing through the T-shaped clamping piece 190, the knife 86 and entering the rear 45 face 194 of the forwardly extending portion of the knife carrier so that the thin flat knife blade 86 may be clamped between the bottom of the groove 186 and the clamping piece 190.

50 The construction and the arrangement of the parts above described is such that in operative position (Figs. 1 and 2) the knife or blade 86 extends downwardly and forwardly of the machine at an angle of about 55 degrees to the horizontal, the plane in which the knife lies being parallel to the axis of the knife carrier cylindrical portion 176. In order that each of the knives 86 will trim the sole along its heel-breast line C as far as 60 the line L (Figs. 11 and 12) to form one of

the shoulders K but will not pass the cutting path of the beveling knives 84 at some points more than others the lower cutting edge 196 (Figs. 5 and 6) of each of the knives 86 is constructed at right angles to the sides 198 70 of the knife and is arranged higher at its inner corner 200 than at its outer corner 202.

As shown in Fig. 2 the knives 86 move along the front edges 204 of the crease plates 66, which front edges extend parallel with the direction of the movement of the knife carrier slide 148, the knives 86 thus being supported against rearward springing by said crease plates. Since the lower cutting edge 196 of each of the knives 86 which engage the upper forward edges of the crease plates is disposed at an angle to the horizontal, as illustrated, each of the knives will cooperate with the upper forward edge of its respective crease plates 66 to constitute a shear couple 80 which will effectively form heel-breast-receiving shoulder K. Although each of the knives is illustrated as having its cutting edge arranged to form an acute angle with the upper forward edge of its respective crease plate thus producing the desired shearing cut to form the heel-breast-receiving shoulder, it will be understood that the cutting edge may be arranged at various angles with reference to the upper forward edge of the crease plate. 85

In order to support and guide the beveling knives 84, each of the sliding beds 92 has a raised portion 206 (Fig. 3) the under side of which has a horizontal dovetailed guideway 208 which extends forwardly and rearwardly 100 parallel to the center of the machine and in which a knife carrier 210 is mounted for movement forwardly and rearwardly of the machine. The upper surfaces of the rear ends of the knife carriers 210 (Fig. 8) are provided with transverse slots 212 receiving a cross-head 214 which is constructed and arranged to move both knives together and to allow the knife carriers 210 to be moved toward and away from one another as the sliding beds 92 are moved toward and away from one another, without causing any relative movement in a direction lengthwise of the knife carriers 210 between the sliding beds 92 and the knife carriers. 105

The cross-head 214 is integral with a dovetailed slider 216 which is constructed and arranged to slide forwardly and rearwardly of the machine in a horizontal slideway 220 (Fig. 1) formed in the bottom portion of the top head 6, the dovetailed slider 216 carrying a depending cam roll 218 that engages the cam groove 82 in the cam 78. Upon rotation of the cam 78 the dovetailed slider 216, through the cross-head 214, moves the knife carriers 210 forwardly and rearwardly of the machine to bevel the marginal portions of the heel portion of the sole in a direction extending lengthwise of the shoe. 110

The under surface of each knife carrier 130

210, along its inner margin 222 (Fig. 8), is beveled to slope toward the center of the machine and upwardly at a steep angle to the horizontal. A knife 84 having an elongated portion with a beveled cutting edge 224 and a flanged portion 228 is fixed to the front face 226 of the knife carrier 210 by means of the flange 228 which is screwed against the said front face 226 of the knife carrier, the knife thus extending forwardly of the knife carrier and having its beveled edge 224 extending laterally of and forming a substantial angle with the flat surface portions 136 of the crease plates and the heel-attaching face of the sole. It is obvious that the angle which the cutting edge of the knife makes with the surface of the sole may be changed as desired, such change being brought about by attaching knives of different angles to the knife-carrying slides.

Since the knives 84 travel in the knife guideways 132 with their cutting edges 224 inclined at an angle to the crease plates 66 and the bottom of the sole, and said knives have their corners 230 moving along the corners 138 of the crease plates, as shown in Fig. 5, it will be clear that the finger portions 130 of the crease plates 66 will extend far enough between the sole F of the shoe and the shoe upper M to protect the upper from being cut by the knives, and the knives will be prevented from springing relatively to the plate as they trim the lateral marginal portions of the sole in the general direction of the length of the shoe.

The lower cutting edge 196 of the shouldering knives 86 are inclined to the heel-attaching face of the sole transversely of the sole substantially at the same inclination as the cutting edges of the beveling knives 84 so as to form a clean cut shoulder at L, the knives being arranged so that they will not substantially cross the paths of one another.

The shaft for rotating the cam 78 which operates the beveling and shouldering knives is actuated by a one-revolution clutch 232 mounted at the rear of the machine and thrown into operation by the hand lever 234.

In order to position the shoe lengthwise in the machine so that the beveling knives and the shouldering knives will operate at correct positions on the sole to form the required heel-seat, mechanism is provided whereby rearward movement of the shoe to be operated upon is halted by contact of the counter portion R (Fig. 4) of the shoe upper against a back gage 282 having a concaved front face 284, the position of the back gage being determined by a heel-engaging mechanism adapted to receive a heel similar to the heel which is to be attached to the shoe. The back gage 282 includes a sliding support 286 (Fig. 1) which is freely slideable forwardly and rearwardly of the machine in a guideway 288 of the middle head 4.

The top head 6 carries heel-engaging and locating mechanism which serves to regulate the position of the back gage 282. For this purpose the sliding support 286 has rigidly fixed thereto an upwardly extending post 290 having its upper end connected to a traveler 292 which slides forwardly and rearwardly of the machine in a guideway 294. An upstanding post 296 is connected to the traveler 292, said post having a threaded hole 298 extending parallel to the length of the slider and receiving a screw 300 having a knurled head 302 at its rear end. The front end of the screw 300 is provided with a collar 304 that lies in a recess 306 (Fig. 2) near the rear of a rear gage plate 308 having a curved recessed portion 310 adapted to engage the rear portion of a heel.

The front of the top head 6 carries a breast gage 312 arranged to engage the breast T of a heel (Fig. 1) which gage is slidably mounted forwardly and rearwardly of the machine in a guideway 316 (Fig. 2) for initial adjustment. The initial adjustment of the gage is effected by means of a screw 318 which passes through an upstanding threaded recess in an upwardly extending portion 320 of the breast gage, said screw being mounted for rotation in an upwardly extending lug 322 on the top head 6 and being provided with a knurled head 324 for conveniently carrying out the initial adjustment of the breast gage.

The top head 6 is also provided with a pair of horizontal guideways 326 positioned laterally of and between the rear gage plate 308 and the breast gage 312 and extending toward the center of and forwardly of the machine. In order to engage the sides S of a heel to center the same, the heel-engaging mechanism includes clamp slides 330 which are adapted to be moved in the guideways 326, each clamp slide carrying clamps 332 connected to the clamp slides 330 by screws 334. The inner ends 336 of the clamps 332 are inclined upwardly and toward one another at an angle of about 75 degrees to the horizontal and preferably carry clamp pieces 338 of rubber or leather so that they will not damage the cover of the heel.

Projecting downwardly from the clamp slides 330 are pivot pins 340 connected by links 342 to other pivot pins 344 that project upwardly from a heel clamp actuator 346, the arrangement and positions of the parts being such that when the clamp slides 330 are in their outermost position the links 342 will appear as a straightened toggle and when the clamp slides are in their innermost position the links appear as a broken toggle as shown in Fig. 2.

The under surface of the rear gage plate 308 and the upper surface of the heel clamp actuator 346 are provided with racks 348, 350 respectively (Fig. 1) which engage a

pinion 352 carried by a compensating block 354, slideable in the guideway 356 in the top head 6 of the machine. The compensating block 354 is operated by a pin 358 extending 5 from one side thereof, the pin being received by a bifurcated portion 360 of an upwardly extending arm 362 (Fig. 2) which is fixed upon a rock shaft 364, mounted for rotation in a bearing 366 supported by the middle 10 head 4.

In order to position the shoe correctly in the machine for the performance of the heel-seat fitting operation, mechanism is provided for engaging the heel which is to be attached 15 to the shoe to be operated on, or a heel like that heel, which mechanism controls the back gage 282 against which the shoe upper is positioned, to determine the extent to which the heel-seat portion of the sole will be 20 trimmed. Provision is also made for normally urging the heel-engaging means in contact with the heel and for urging the back gage forwardly of the machine. Means is also provided to lock the back gage against 25 rearward movement under pressure of the shoe, this locking means being adapted to hold the back gage in its foremost position and to hold the heel-engaging means against the heel.

30 Keyed to the outer end of the rock shaft 364 is a hub 366 (Fig. 9) carrying an upright arm 368 having a yoke portion 370 (Figs. 9 and 10) in which is mounted a pawl pin 372. Extending axially from the hub 366 are a 35 pair of projecting lugs 374 which are adapted to be engaged by a pair of axially extending lugs 376 upon a lever 378 loosely mounted upon the rock shaft 364. A treadle rod 380 is pivoted to the lever 378 and forwardly extending from said lever 378 is an arm 382 carrying a spring 384 for holding the arm 382 normally in a downward position. Clockwise movement of the arm 382 through mechanism carried by the yoke 370, which mechanism 40 will be later described, causes the upright arm 368 to move in a clockwise direction (Fig. 10), thereby moving the compensating block 354 toward the front of the machine. Conversely upon depressing the treadle rod 45 380 the lugs 376 abut against the lugs 374 rotating the upright arm 368 in a counterclockwise direction thereby moving the compensating block 354 rearwardly of the machine, the compensating block carrying with it the 50 pinion 352 which engages the rear gage plate 308 and the heel clamp actuator 346 to move these two parts rearwardly of the machine. Rearward movement of the heel clamp actuator 346 causes the clamps 332 to move away 55 from one another by reason of the toggle action of the links 342. The clamping means for holding the heel in the heel-engaging means are thus opened to permit a new heel to be inserted, which heel is placed with its attaching face downwardly upon the top sur-

face 386 of the horizontal plate 388 (Fig. 1) and with its breast T resting against the breast gage 312. Upon the release of the treadle rod 380 the spring 384 through the upright arm 368 and mechanism carried thereby, which will later be described, causes the compensating block 354 to move forwardly of the machine carrying with it the rear gage plate 308 and heel clamp actuator 346. Should the rear gage plate 308 come into contact with the heel before the clamps 332, the compensating block 354 will continue to move forwardly, the pinion 352 rolling upon the ratchet teeth 348 of the rear gage plate and urging the heel clamp actuator 346 forwardly until the heel clamps contact with the side of the heel, at which time forward movement of the compensating block ceases, the heel being held in position by the treadle spring 384.

80 A convenient form of locking mechanism for the heel-engaging mechanism and the back gage 282 is shown as embodying a device which locks the back gage 282 as well as the rear gage plate 308 and the heel clamps 332 for holding the heel firmly in the heel-engaging means.

85 The locking mechanism comprises a ratchet disk 390 mounted on the frame of the machine and engaged by a depending pawl 392 mounted upon an eccentric sleeve 394 carried by the pawl pin 372 and provided with a pawl spring 396 fastened in the yoke 370 for urging the pawl into engagement with the ratchet disk 390. The eccentric sleeve 394 has a laterally depending arm which will be referred to as the eccentric actuator 398 and projecting forwardly of the machine from the eccentric actuator is an arm 400 connected by a spring 402 to the arm 382, the arrangement of parts being such that the eccentric actuator 398 is normally in a substantially upright position (Fig. 10) during the trimming operation of the machine.

90 The lever 378 which is free to rock on the shaft 364 and carries projecting lugs 376 arranged to engage the lugs 374 of the hub 366 is provided with an upstanding ear 404 which is adapted to engage a laterally extending portion 406 of the pawl 392 so as to rock the pawl in a clockwise direction to raise the pawl 392 from the ratchet disk 390 prior to the time that the lugs 376 of the lever 378 engage the lugs 374 of the hub 366. Upon depression of the treadle rod 380 the upstanding ear 404 moves in a counterclockwise direction, as viewed in Fig. 10, and lifts the pawl 392 from engagement with the ratchet disk 390. Upon further depression of the treadle rod, the lugs 376 on the lever 378 engage the lugs 374 of the hub 366 and rock the upright arm 368 in a counterclockwise direction (Fig. 10) carrying with it the rock shaft 364 which moves the compensating block 354 rearwardly of the machine, there-

by moving the back gage rearwardly of the machine and opening the heel-engaging device for the removal of the heel. A new heel is then inserted in the heel-engaging means and the pressure of the treadle is released 5 allowing the spring 384 to move the lever 378 in a clockwise direction. As the lever moves in a clockwise direction, its upstanding ear 404 engages the eccentric actuator 398 to throw the pawl 392 against the ratchet disk 390 and to rock the upstanding arm 368 in a clockwise direction (Fig. 10). Since the upstanding arm 368 is actuated in a clockwise direction through contact of the upstanding ear 404 of the lever 378 with the eccentric actuator 398, the pawl 392 will at all times be pressed down upon the ratchet disk to prevent backlash, the parts of the mechanism thus being held against backward movement. 10 In carrying out the heel-seat fitting operation the operator depresses the treadle rod 380 to open the heel-engaging means and places a covered heel in said heel-engaging means with its breast engaging the heel-breast gage 312 which has been initially adjusted. The treadle rod 380 is then released whereupon the heel clamps 332 move inwardly from the sides of the heel and the rear gage plate 308 moves forwardly of the 15 machine to grip the heel and lock the same in place, the back gage at the same time being automatically positioned to determine the length of the heel-seat to be trimmed. 20

The operator next places the inverted shoe 25 upon the shoe-supporting plate 30 with its heel end toward the machine and slides the work support 12 rearwardly until the rear end of the shoe engages with and is stopped by the back gage 282, the shoe-supporting plate 30 being depressed by hand against the pressure of spring 36 so that the thin finger portions 130 of the crease plates 66 may enter the crease between the shoe upper and the sole. 30

The treadle 72 is then depressed causing the sliding beds 92 to be moved toward one another and the crease plates 66 further to enter the crease between the upper of the shoe and the sole. As the treadle 72 is still 35 further depressed the post 20 is moved upwardly and as the treadle 72 comes near the bottom of its stroke the holdown clamp 112 is brought into operative position upon the heel-attaching face of the sole of the shoe 40 (Fig. 4), the crease plates continuing to enter between the shoe upper and the sole until they are stopped by the line of stitching A. During the heel-seat fitting operation the treadle 72 is kept depressed to hold the 45 parts in their relative positions, the sole being substantially flat with its marginal portions undistorted by the entrance of the crease plates.

When the shoe has been placed in operating 50 position the operator next depresses the

hand lever 234 which allows the one-revolution clutch 232 to rotate the cam 78 a single revolution, thus actuating the beveling knives 84 and the shouldering knives 86. It is generally customary to make the beveling cuts before the shoulder cuts but the order of operation of the knives may be changed if desired. When the pressure on the treadle 72 is released the sliding beds 92 are automatically moved away from one another and the hold-down clamp 112 is automatically raised from the sole of the shoe. Finally the work support 12 which is now unlocked is moved away from the machine to remove the shoe and the treadle rod 380 is depressed to remove the heel from the heel-engaging mechanism. 70

While the machine has been described as comprising the beveling knives 84 and the shoulder forming knives 86, it will be understood that the machine is designed to fit the heel-seat portions of shoes which have been previously trimmed lengthwise thereof. In order to condition the machine for operating upon a shoe the sole of which has been particularly fitted as above indicated, the knives 84 are first removed from the machine and a shoe supported upon the jack is positioned lengthwise thereof in the machine by the back gage 282 as already explained. After the shoe has been positioned in the machine the marginal portions of the heel-seat portion of the sole, which have been partially severed from the sole, are removed from the sole and heel-breast-receiving shoulders formed upon the sole by moving the shouldering knives 86 transversely of the sole as above described. 100

While the hold-down clamp 112 has been described and illustrated as part of the machine, it has been found that such a clamp is not an essential element in the heel-seat trimming operation since the crease plates may be constructed to resist the upward pressure of the post 20 and to hold the shoe in position to have its heel-seat fitted while the sole is in an undistorted condition. When using the machine without a holdown clamp, crease plates may be employed which are gradually thickened toward their rear portions 414, as shown in Fig. 13, so that they will be stout enough to stand the upward pressure called for in a machine of this nature without being thick enough to distort the sole. 110

It is sometimes the practice not to sew the sole of the shoe to the shoe upper rearwardly of the heel-breast line and under these conditions there is no line of stitching to limit the penetration of the crease plates between the shoe upper and the sole of the shoe. In order to fit heel-seats on shoes of this character as well as on shoes having soles which have been attached to the shoe rearwardly of the breast line, the form of crease plates illustrated in Fig. 7 may be used. These crease plates are 120

substantially the same as the crease plates above described, except that each of them is provided with a depending portion 410 (Fig. 7) which portion is adapted to conform to 5 the general lateral outline of the last 412 upon which, as illustrated in Fig. 7, the shoe is mounted, so that the penetration of the crease plates into the crease between the shoe upper and the sole is limited by the engagement of the depending portions of the crease plates against the counter portion of the shoe upper.

Having described the invention, what we claim as new and desire to secure by Letters 15 Patent of the United States is:—

1. A heel-seat fitting machine having, in combination, a shoe support, crease plates constructed and arranged to enter the rand 20 crease of a shoe on the support, a pair of knives mounted for reciprocation in the general direction of the length of the shoe for trimming the marginal portions of the heel-seat portion of the sole, and a pair of knives mounted for rectilinear movement trans- 25 versely of the length of the shoe to form shoulders substantially at the heel breast line of the sole.

2. A heel-seat fitting machine constructed and arranged to operate upon the heel portion 30 of a sole which is attached to a shoe upper and is in an undistorted condition having, in combination, a shoe support, crease plates constructed and arranged to enter the rand crease of a shoe carried by the support 35 without distorting the sole, a pair of knives mounted for reciprocation in the general direction of the length of the shoe for trimming the marginal portions of the heel-seat portion of the sole, and a pair of knives mounted 40 for reciprocation transversely of the length of the shoe substantially at the heel breast line of the sole completely to sever the material trimmed from the marginal portions of the heel-seat portion of the sole and to form 45 heel breast receiving shoulders.

3. A heel-seat fitting machine constructed and arranged to operate upon the heel portion 50 of a sole which is attached to a shoe and is in an undistorted condition having, in combination, a shoe support, crease plates constructed and arranged to enter the rand crease of a shoe carried by the support without distorting the sole, a pair of knives mounted 55 for reciprocation in the general direction of the length of the shoe for trimming the marginal portions of the heel-seat portion of the sole at a steep inclination to the heel-attaching face of the sole, and a pair of knives mounted for reciprocation transversely of the 60 length of the shoe to form shoulders substantially at the heel breast line of the sole.

4. A heel-seat fitting machine having, in combination, a shoe support, a pair of knives mounted for reciprocation in the general direction of the length of the shoe carried by

the support for trimming the marginal portions of the heel-seat portion of the sole at a steep inclination to the heel-attaching face of the sole of the shoe to form a wide heel-seat portion of the sole having the full thickness of the sole throughout substantially its entire width, and a pair of knives mounted for reciprocation in substantially rectilinear paths transversely of the shoe and substantially at the heel breast line of the sole to form heel breast receiving shoulders.

5. A heel-seat fitting machine having, in combination, a shoe support, crease plates constructed and arranged to enter the rand crease of a shoe on the support, a pair of knives mounted for reciprocation in the general direction of the length of the shoe for trimming the marginal portions of the heel-seat portion of the sole, a pair of knives having rectilinear movement and mounted for reciprocation transversely of the length of the shoe substantially at the heel breast line of the sole for forming heel breast receiving shoulders on the sole, and a clamp located between the first-named knives and constructed and arranged to engage the heel-attaching face of the sole of the shoe.

6. A heel-seat fitting machine constructed and arranged to operate upon the heel-seat portion of a sole which is attached to a shoe upper and is in an undistorted condition having, in combination, a shoe support, crease plates constructed and arranged to enter the rand crease of a shoe on the support without distorting the sole, a pair of drag knives mounted for reciprocation lengthwise of the sole of a shoe for trimming the marginal portions of the heel-seat portion of the sole at a steep inclination to the heel-attaching face of the sole, and means for reciprocating said knives relatively to the shoe.

7. A heel-seat fitting machine having, in combination, means constructed and arranged to support a shoe having a sole attached thereto, and a pair of knives mounted for reciprocation substantially lengthwise of the supported shoe and having cutting edges inclined at a substantial angle to the heel-attaching face of the sole to trim the lateral marginal portions of the heel-seat portion of the sole at an inclination to the heel-attaching face of the sole.

8. A heel-seat fitting machine having, in combination, means constructed and arranged to support a shoe having a sole attached thereto, and a pair of knives mounted for reciprocation lengthwise of the supported shoe and inclined at a substantial angle to and extending laterally of the heel-attaching face of the sole to trim the marginal portions of the heel-seat portion of the sole at a steep inclination to the heel-attaching face of the sole.

9. A heel-seat fitting machine having, in combination, a shoe support, crease plates

constructed and arranged to enter the rand 5 crease of a shoe carried by the support, and a pair of knives mounted for reciprocation lengthwise of the shoe and inclined to the heel-attaching face of the sole for trimming the marginal portions of the heel-seat portion of the sole at steep inclinations to the heel-attaching face of the sole.

10. A heel-seat fitting machine constructed 10 and arranged to operate upon the heel-seat portion of a sole which is attached to a shoe upper and is in an undisturbed condition having, in combination, a shoe support, a pair of drag knives constructed and arranged to 15 operate upon the sole of a shoe carried by the support while the sole is in an undistorted condition for trimming the marginal portions of the heel-seat portion of the sole at a steep inclination to the heel-attaching 20 face of the sole.

11. A heel-seat fitting machine having, in combination, a shoe support, crease plates constructed and arranged to enter the rand 25 crease of a shoe on the support, knives mounted for movement in the general direction of length of the shoe, the knives being constructed and arranged simultaneously to trim the lateral marginal portions of the heel-seat 30 portion of the sole while the sole is in an undistorted condition, and a pair of knives mounted for reciprocation transversely of the length of the sole to form heel breast receiving shoulders substantially at the breast line of the heel.

35 12. A heel-seat fitting machine having, in combination, a shoe support, crease plates constructed and arranged to enter the rand crease of a shoe on the support, knives mounted for movement in the general direction of 40 the length of the shoe, the knives being constructed and arranged to trim surplus material from the marginal portions of the sole of the shoe as they move forwardly of the sole to reduce the heel-seat portion thereof, 45 and a knife positioned at each side of the sole and mounted for movement transversely of the shoe, to form heel breast receiving shoulders substantially at the heel breast line of the sole, each of the last-named knives having a cutting edge set at an angle relatively to the heel-attaching face of the sole.

50 13. A heel-seat fitting machine having, in combination, a shoe support, crease plates constructed and arranged to enter the rand 55 crease of a shoe on the support without distorting the sole, knives mounted for movement in the general direction of length of the shoe, the knives being constructed and arranged to trim a lateral marginal portion 60 of the heel-seat portion of the sole, and a pair of knives mounted for movement transversely to the length of the sole from the sides of the sole to form heel breast receiving shoulders while the sole is in an undistorted 65 condition, said knives having cutting edges

inclined at an angle to and extending transversely of the heel-attaching face of the sole.

14. A heel-seat fitting machine having, in combination, a shoe support, crease plates constructed and arranged to enter the rand 70 crease of a shoe on the support and having knife-guideways in their sole engaging surfaces, and a pair of knives mounted for reciprocation lengthwise of the sole and constructed and arranged to travel in the knife-guideways of the crease plates to trim the marginal portions of the heel-seat portion of the sole.

15. A heel-seat fitting machine having, in combination, a shoe support, crease plates 80 constructed and arranged to enter the rand crease of a shoe on the support and having knife-guideways in their sole engaging surfaces, a pair of knives mounted for reciprocation lengthwise of the sole and constructed and arranged to travel in the knife-guideways of the crease plates to trim the marginal portions of the heel-seat portion of the sole at a steep inclination relatively to the heel-attaching face of the sole, and means for reciprocating said knives relatively to the shoe. 90

16. A heel-seat fitting machine constructed and arranged to operate upon the heel-seat portion of a sole which is attached to a shoe and is in an undistorted condition having, in combination, a shoe support, crease plates 95 constructed and arranged to enter the rand crease of a shoe on the support without distorting the sole and having knife-guideways in their sole engaging surfaces, and a pair of knives mounted for reciprocation lengthwise of the sole and constructed and arranged to travel in the knife-guideways of the crease plates to trim the marginal portions of the heel-seat portion of the sole in the general direction of the length of the shoe. 100

105 17. A heel-seat fitting machine having, in combination, a shoe support, crease plates constructed and arranged to enter the rand crease of a shoe on the support and having knife-guideways in their sole engaging surfaces, and a pair of knives mounted for reciprocation substantially lengthwise of the shoe and inclined at a substantial angle to the heel-attaching face of the sole and constructed and arranged to travel in the knife-guideways of the crease plates for trimming the marginal portions of the heel-seat portion of the sole lengthwise of the shoe at a steep inclination to the heel-attaching face of the sole. 110

115 18. A heel-seat fitting machine having, in combination, a shoe support, crease plates constructed and arranged to enter the rand crease of a shoe on the support, beveling knives inclined to and extending transversely of the heel-attaching face of the sole of the shoe each of the knives being constructed and arranged for movement in the general direction of the length of the shoe to trim a marginal portion of the sole of the shoe to 120

125 130

form a heel-seat portion thereof, and shou-
dering knives for forming heel-breast re-
ceiving shoulders mounted for movement
transversely of the sole of the shoe and in-
clined at substantially the same inclination
to and transversely of the heel-attaching face
of the sole of the shoe as the beveling knives.

19. A heel-seat fitting machine constructed
and arranged to form a wide heel-seat having
its full thickness throughout substantially
its entire width having, in combination, a
shoe support, crease plates constructed and
arranged to enter the rand crease of a shoe
on the support without distorting the sole
and having knife-guideways in their sole
engaging surfaces, and a pair of knives
mounted for reciprocation substantially
lengthwise of the shoe and inclined at a sub-
stantial angle to the heel-attaching face of
the sole of the shoe constructed and arranged
to travel in the knife-guideways of the crease
plates for trimming the marginal portions of
the heel-seat portion of the sole lengthwise
of the shoe at a steep inclination to the heel-
attaching face of the sole while the sole is
in an undistorted condition.

20. A heel-seat fitting machine having, in
combination, a shoe support, crease plates
constructed and arranged to enter the rand
crease of a shoe carried by the support and
having knife-guideways in their sole engag-
ing surfaces, a pair of knives mounted for
reciprocation substantially lengthwise of the
sole of a shoe and constructed and ar-
ranged to travel in the knife-guideways of
the crease plates to trim the marginal por-
tions of the heel-seat portion of the sole at a
steep inclination relatively to the heel-attach-
ing face of the sole of the shoe, and means
for reciprocating said knives relatively to
the shoe.

21. A heel-seat fitting machine having, in
combination, a shoe support, crease plates
constructed and arranged to enter the rand
crease of a shoe on the support and having
knife-guideways in their sole engaging sur-
faces, a pair of knives mounted for reciproca-
tion lengthwise of the sole of a shoe and con-
structed and arranged to travel in the knife-
guideways for trimming the marginal por-
tions of the heel-seat portion of the sole at a
steep inclination to the heel-attaching face
of the sole, means for reciprocating said
knives relatively to the shoe, and a holddown
55 clamp located between the knives and con-
structed and arranged to engage the heel-
attaching face of the sole during the
trimming operation.

22. A heel-seat fitting machine having, in
combination, a shoe support, crease plates
constructed and arranged to enter the rand
crease of a shoe on the support and having
knife-guideways in their sole engaging sur-
faces, a pair of knives mounted for reciproca-
tion substantially lengthwise of the shoe and

inclined at a substantial angle to the heel-
attaching face of the sole and constructed
and arranged to travel in the knife-guideways
for trimming the marginal portions of
the heel-seat portion of the sole at a relatively
steep inclination to the heel-attaching face
of the sole, a pair of knives mounted for re-
ciprocation transversely of the length of the
shoe substantially at the heel breast line of
the sole to form heel breast receiving shoul-
ders, and a holddown clamp located between
the knives and constructed and arranged to
engage the heel-attaching face of the sole
during the trimming operation.

23. A heel-seat fitting machine constructed
and arranged to operate upon the heel-seat of
a sole which is attached to a shoe and is in
an undistorted condition having, in combina-
tion, a shoe support, crease plates construct-
ed and arranged to enter the rand crease of
a shoe on the support without distorting the
sole and having knife-guideways in their
sole engaging surfaces, a pair of knives for
trimming the undistorted sole of the shoe
mounted for reciprocation lengthwise of the
sole of a shoe and constructed and arranged
to travel in the knife-guideways for trim-
ming the marginal portions of the heel-seat
portion of the sole at a steep inclination to
the heel-attaching face of the sole, means for
reciprocating said knives relatively to the
shoe, and a holddown clamp located between
the knives and constructed and arranged to
engage the heel-attaching face of the heel-
seat.

24. A heel-seat fitting machine having, in
combination, a shoe support, crease plates
constructed and arranged to enter the rand
crease of a shoe on the support, a pair of
knives mounted for reciprocation substan-
tially lengthwise of the shoe and inclined at a
substantial angle to the heel-attaching face of
the sole for trimming the marginal portions
lengthwise of the heel-seat portion of the sole
at a relatively steep inclination to the heel-
attaching face of the sole, and a holddown
clamp positioned between said knives con-
structed and arranged to engage the heel-
attaching face of the sole.

25. A heel-seat fitting machine construct-
ed and arranged to operate upon the heel-
seat portion of a sole which is attached to a
shoe and is in an undistorted condition hav-
ing, in combination, a shoe support, crease
plates constructed and arranged to enter the
rand crease of a shoe on the support without
distorting the sole, a pair of knives construct-
ed and arranged to operate upon the undis-
torted sole of a shoe for trimming the mar-
ginal portions of the heel-seat portion of the
sole lengthwise of the shoe at a relatively
steep inclination to the heel-attaching face
of the sole, and a holddown clamp arranged
to engage the heel-attaching face of the heel-
seat.

26. A heel-seat fitting machine constructed and arranged to operate upon the heel portion of a sole which is attached to a shoe and is in an undistorted condition having, in combination, a shoe support, crease plates constructed and arranged to enter the rand crease of a shoe on the support without distorting the sole, a back gage for positioning the shoe relatively to the crease plates lengthwise of the shoe, a holddown clamp constructed and arranged to engage the heel portion of the sole, means for operating the crease plates, the shoe support and the hold-down clamp to hold the shoe in position to be operated upon, means for varying the pressure of the clamp upon the heel portion of the shoe, and means for trimming the heel portion of the sole to form the heel-seat portion of the sole while the sole is in an undistorted condition. 10
27. A heel-seat fitting machine constructed and arranged to operate upon the heel portion of a sole which is attached to a shoe and is in an undistorted condition having, in combination, a shoe support, crease plates constructed and arranged to enter the rand crease of a shoe on the support without distorting the sole, a back gage for positioning the shoe relatively to the crease plates lengthwise of the shoe, a heel-engaging means for automatically positioning the back gage, a holddown clamp arranged to engage the heel portion of the sole of a shoe, means for operating the crease plates, shoe support and clamp to hold the shoe in position to be operated upon, and means for trimming the sole to form the heel-seat portion of the sole. 15
28. A heel-seat fitting machine having, in combination, means to support a shoe having a sole attached thereto, crease plates constructed and arranged to enter the rand crease of a shoe on the supporting means, a back gage for positioning the shoe relatively to the crease plates lengthwise of the shoe, a holddown clamp constructed and arranged to engage the heel-seat portion of the sole of a shoe, common controlling means to operate in sequence the crease plates, shoe supporting means and the clamp, and means to trim the sole for forming the heel-seat portion of the sole. 20
29. A heel-seat fitting machine having, in combination, means to support a shoe having a sole attached thereto crease plates constructed and arranged to enter the rand crease of a shoe on the supporting means, a back gage for positioning the shoe relatively to the crease plates lengthwise of the shoe, a heel-engaging means for automatically positioning the back gage, a holddown clamp constructed and arranged to engage the heel-seat portion of the sole of a shoe, common controlling means to operate in sequence the crease plates, shoe supporting means and clamp, and means to trim the sole for forming the heel-seat portion of the sole. 25
30. A heel-seat fitting machine constructed and arranged to operate upon the heel portion of a sole which is attached to a shoe and is in an undistorted condition having, in combination, a shoe support, crease plates constructed and arranged to enter the rand crease of a shoe on the support without distorting the sole, a back gage for positioning the shoe relatively to the crease plates lengthwise of the shoe, a holddown clamp constructed and arranged to engage the heel portion of the sole, means for operating the crease plates, the shoe support and the hold-down clamp to hold the shoe in position to be operated upon, means for varying the pressure of the clamp upon the heel portion of the shoe, and means for trimming the heel portion of the sole to form the heel-seat portion of the sole while the sole is in an undistorted condition. 30
31. A heel-seat fitting machine having, in combination, means to support a shoe having a sole attached thereto, crease plates constructed and arranged to enter the rand crease of a shoe on the supporting means, a back gage for positioning the shoe relatively to the crease plates lengthwise of the shoe, a holddown clamp constructed and arranged to engage the heel-seat portion of the sole, common controlling means for operating in sequence the crease plates, the shoe supporting means and the clamp, means for varying the timing of the clamp with respect to the crease plates and the shoe supporting means, and means for trimming the sole to form the heel-seat portion of the sole. 35
32. A heel-seat fitting machine having, in combination, a shoe support, crease plates constructed and arranged to enter the rand crease of a shoe on the support, a back gage for positioning the shoe relatively to the crease plates lengthwise of the shoe, a heel-engaging means for automatically positioning the back gage to regulate the position of the shoe, a holddown clamp constructed and arranged to engage the heel portion of the sole of the shoe, common controlling means for operating in sequence the crease plates, the shoe support and the clamp to hold the shoe in position to be operated upon, means for centering the heel within the heel-engaging means, and means for trimming the sole to form the heel-seat portion of the sole. 40
33. A heel-seat fitting machine having, in combination, a shoe support, crease plates constructed and arranged to enter the rand crease of a shoe on the support, a machine frame, a pair of sliding beds mounted for transverse movement upon the machine frame relatively to the shoe, means for moving the sliding beds toward and away from one another, a reciprocating knife carried by each of the sliding beds and arranged to move lengthwise of the sole of the shoe to trim the marginal portions of the sole to form a heel-seat portion of a sole, another knife carried by each of the sliding beds and constructed and arranged to move transversely 45

of the shoe substantially at the heel breast line of the sole to form a heel breast receiving shoulder, and means for reciprocating the knives relatively to the sliding beds and the support for forming the heel-seat portion of the sole. 5

34. A heel-seat fitting machine having, in combination, a shoe support, a machine frame, a pair of sliding beds mounted for transverse movement in the machine frame toward and away from one another, crease plates constructed and arranged to enter the rand crease of a shoe on the support, which plates are carried by the sliding beds, means for moving the sliding beds toward and away from one another, a reciprocating knife carried by each of the sliding beds and arranged to move lengthwise of the sole of the shoe to trim the marginal portions of a heel-seat portion of the sole, another knife carried by each of the sliding beds and arranged to move transversely of the length of the shoe to form heel breast receiving shoulders substantially at the heel breast line of the sole, and means for reciprocating the knives relatively to the sliding beds and the support for forming the heel-seat portion of the sole. 10

35. A heel-seat fitting machine having, in combination, a shoe support, a machine frame, a pair of sliding beds mounted for movement toward and away from one another in the machine frame, a knife carried by each of the sliding beds which knife is mounted for reciprocation lengthwise of the sole of a shoe on the support, another knife carried by each sliding bed and arranged to move transversely of the length of the shoe to form heel breast receiving shoulders substantially at the heel breast line of the sole, 30 means for actuating the lengthwise moving knives relatively to the shoe support and sliding beds, means for actuating the transversely moving knives relatively to the shoe support and sliding beds, and means for initially 40 setting the transversely moving knives in a correct position relatively to the sliding beds. 45

36. A heel-seat fitting machine having, in combination, a shoe support for presenting a shoe, heel first and bottom side up to the machine, a machine frame, a pair of sliding beds mounted for movement toward and away from one another transversely of the machine in the machine frame, a pair of crease plates mounted upon the sliding beds and 50 arranged to enter the rand crease of the shoe, a pair of reciprocating knives carried by and guided in the sliding beds and constructed and arranged to trim the marginal portions of a sole lengthwise of the shoe to form a heel-seat portion of the sole, another pair of knives carried by and guided in the sliding beds and arranged to move substantially at 55 right angles to the aforesaid knives to form shoulders substantially at the heel breast line of the sole, means for moving the sliding 60 beds toward and away from one another to bring the crease plates into and out of operative position, and means for actuating the knives relatively to the sliding beds and the shoe support for forming the heel-seat portion of the sole. 70

37. A heel-seat fitting machine having, in combination, a shoe support, a pair of crease plates constructed and arranged to enter the rand crease of a shoe on the support, a pair of sliding beds having upwardly extending portions, said beds being movable toward and away from one another in a direction laterally of the shoe, a pair of knives carried by and guided for reciprocation in the general direction of the length of the shoe in the upwardly extending portions of the sliding beds and having relative movement to the beds and to the shoe support, and means for actuating said knives, said actuating means comprising means whereby the knives may be moved toward and away from one another in a direction substantially at right angles to their normal cutting direction without effecting any movement of the knives in their normal cutting direction. 75

38. A heel-seat fitting machine having, in combination, a shoe support, a machine frame, a pair of sliding beds mounted for movement toward and away from one another in the machine frame, a pair of crease plates constructed and arranged to enter the rand crease of a shoe on the support, which plates are carried by each of the sliding beds, a knife carried by each of the sliding beds which knife is constructed and arranged to move in the general direction lengthwise of the sole of the shoe to be operated upon and is guided for reciprocation in said sliding beds, and a second knife carried by each of the sliding beds and moving transversely of the sole of the shoe to form heel breast receiving shoulders substantially at the heel breast line of the shoe, said second knives operating upon the sole of the shoe at places located forward of that portion of the shoe engaged by said crease plates. 90

39. A heel-seat fitting machine having, in combination, a shoe support, a machine frame, a pair of sliding beds mounted for movement toward and away from one another in the machine frame, a pair of crease plates constructed and arranged to enter the rand crease of a shoe on the support and having knife-guideways in their sole-engaging surfaces, and a knife positioned in each guideway and carried by each of the sliding beds arranged to be moved lengthwise of the sole of the shoe to be trimmed and guided for reciprocation in said sliding beds. 105

40. A heel-seat fitting machine having, in combination, a shoe support, crease plates constructed and arranged to enter the rand crease of a shoe on the support and having knife-guideways in their sole-engaging sur- 110 115 120 125

- faces, a pair of sliding beds having movement toward and away from one another, and a pair of knives mounted for movement in the general direction of the length of the shoe and carried by the sliding beds, said knives being constructed and arranged to trim surplus material from the marginal portions of the sole to form a heel-seat portion of the sole, and being inclined to and transversely of the heel-attaching face of the sole, the outside corners of the knives being positioned in the knife-guideways, and the inner corners of the knives being positioned at a higher elevation than the outer corners of the knives.
41. A heel-seat fitting machine having, in combination, a shoe support, crease plates constructed and arranged to enter the rand crease of a shoe on the support and having knife-guideways in their sole-engaging surfaces, a pair of sliding beds arranged for movement toward and away from one another, a pair of knives carried by the sliding beds and arranged to move in the general direction of the length of the shoe to trim surplus material from the marginal portions of the sole of the shoe to form a heel-seat portion of the sole, said knives being inclined to and transversely of the heel-attaching face of the sole, the outside corners of the knives being arranged to travel in the aforesaid knife-guideways, the inner corners of the knives being raised substantially higher than the outer corners of the knives, and a pair of shouldering knives carried by the sliding beds and constructed and arranged to be moved transversely of the sole, both pairs of knives being arranged to be moved with the sliding beds and also constructed and arranged to be moved relatively to the sliding beds.
42. A heel-seat fitting machine having, in combination, a shoe support, a machine frame, a pair of sliding beds mounted for movement toward and away from one another in the machine frame, a pair of crease plates constructed and arranged to enter the rand crease of a shoe on the support and having knife-guideways in their sole engaging surfaces, a knife carried by each of the sliding beds and arranged to be moved in a general direction lengthwise of the shoe, said knives being carried by and guided for reciprocation in said sliding beds and positioned in the knife-guideways of the crease plates, and another knife carried by each of the sliding beds and constructed and arranged to be moved transversely of the shoe to form heel breast receiving shoulders substantially at the heel breast line of the sole, said last-named knives operating upon the sole of the shoe at places located forward of that portion of the shoe engaged by said crease plates.
43. A heel-seat fitting machine having, in combination, a shoe support, a machine frame, a pair of sliding beds mounted for

- movement toward and away from one another in the machine frame, a pair of crease plates constructed and arranged to enter the rand crease of a shoe on the support and having knife-guideways in their sole engaging surfaces, a knife carried by each of the sliding beds and arranged to be moved in the general direction lengthwise of the shoe, said knives being guided for reciprocation in said sliding beds and positioned in the knife-guideways of the crease plates, and means for forming heel breast receiving shoulders substantially at the heel breast line of the sole.
44. A heel-seat fitting machine having, in combination, a shoe support, a machine frame, a pair of sliding beds mounted for movement toward and away from one another in the machine frame, a pair of crease plates constructed and arranged to enter the rand crease of a shoe on the support and having knife-guideways in their sole engaging surfaces, a knife carried by each of the sliding beds and arranged to be moved in the general direction lengthwise of the shoe, said knives being guided for reciprocation in said sliding beds and positioned in the knife-guideways of the crease plates, and a knife carried by each of the sliding beds and arranged to be moved transversely of the shoe to form heel breast receiving shoulders substantially at the heel breast line of the sole.
45. A heel-seat fitting machine having, in combination, a shoe support, a machine frame, a pair of sliding beds mounted for movement toward and away from one another in the machine frame, a pair of crease plates constructed and arranged to enter the rand crease of a shoe on the support, which plates are carried by the sliding beds and have knife-guideways in their sole engaging surfaces, a knife carrier supported by and guided for reciprocation in each of said beds and arranged to be moved in the general direction lengthwise of the shoe, and a knife carried by each of the knife carriers and arranged to be positioned in each knife-guideway.
46. A heel-seat fitting machine having, in combination, a shoe support, a machine frame, a pair of sliding beds mounted for movement toward and away from one another in the machine frame, a pair of crease plates constructed and arranged to enter the rand crease of a shoe on the support, which plates are carried by the sliding beds and have knife-guideways in their sole engaging surfaces, a knife carrier supported by and guided for reciprocation in each of the sliding beds and arranged to be moved in the general direction lengthwise of the shoe, a knife carried by each of the knife carriers and arranged to be positioned in each knife-guideway, and another knife carried by each of the sliding beds and arranged to be moved

transversely of the shoe to form heel breast receiving shoulders substantially at the heel breast line of the sole.

47. A heel-seat fitting machine having, in combination, a shoe support, a machine frame, a pair of sliding beds mounted for movement toward and away from one another in the machine frame, a pair of crease plates constructed and arranged to enter the rand crease of a shoe on the support, which plates are carried by the sliding beds and have knife-guideways in their sole engaging surfaces, a knife carrier supported by and guided for reciprocation in each of the sliding beds and arranged to be moved in the general direction lengthwise of the shoe, a knife carried by each of the knife carriers and arranged to be positioned in each knife-guideway, and another knife carried by each of the sliding beds and arranged to be moved transversely of the shoe to form heel breast receiving shoulders substantially at the heel breast line of the sole, said last-named knives operating upon the sole at places located forward of that portion of the shoe engaged by said crease plates.

48. A heel-seat fitting machine having, in combination, a shoe support, crease plates constructed and arranged to enter the rand crease of a shoe carried by the support, means for trimming the sole of the shoe to form a heel-seat portion of the sole, and guideways in the sole engaging surfaces of said crease plates for directing the trimming means.

49. A heel-seat fitting machine having, in combination, a shoe support, crease plates constructed and arranged to enter the rand crease of a shoe on the support and having knife-guideways in their sole-engaging surfaces, and a pair of knives mounted for movement in the general direction of the length of the shoe for trimming surplus material from the marginal portions of the sole of the shoe to form a heel-seat portion of the sole, said knives being inclined to and transversely of the heel-attaching surface of the sole of the shoe, the outside corners of the knives being positioned in the aforesaid knife-guideways, the inner corners of the knives being positioned at a higher elevation than the outer corners of the knives.

50. A heel-seat fitting machine having, in combination, a shoe support, and a pair of crease plates, knives for trimming a sole to form a heel-seat, each of said crease plates having a knife-guideway in its sole engaging surface to receive one of the trimming knives and having a thin finger portion constructed and arranged to enter the rand crease of a shoe on the support without distorting the sole.

51. A heel-seat fitting machine constructed and arranged to operate upon the heel-seat portion of the sole of a shoe which is attached to the shoe upper and is in an undis-

torted condition having, in combination, a shoe support, a pair of crease plates, each of which has a thin finger portion constructed and arranged to enter the rand crease of the shoe on the support without distorting the sole, and drag knives mounted for movement lengthwise of the sole and along opposite sides of the sole and constructed and arranged simultaneously to reduce the width of the heel-seat portion of the sole.

52. A heel-seat fitting machine having, in combination, a shoe support, a pair of crease plates constructed and arranged to enter the rand crease of a shoe on the support, and means for trimming the sole of a shoe to form a heel-seat portion of the sole, each crease plate having a guide in its sole engaging face in which guide the trimming means is positioned, and each crease plate having a thin finger portion, one side of which portion is a continuation of the said guide.

53. A heel-seat fitting machine having, in combination, a shoe support, a machine frame, a pair of sliding beds mounted for movement toward and away from one another in the machine frame, a pair of crease plates having knife-guideways in their sole engaging surfaces and having thin tapered fingers constructed and arranged to enter the rand crease of a shoe on the support without distorting the sole, and a knife carried by each of the sliding beds and arranged to move in the general direction lengthwise of the shoe and positioned in the knife-guideways for forming the heel-seat portion of the sole.

54. A heel-seat fitting machine having, in combination, a shoe support, a pair of crease plates constructed and arranged to enter the rand crease of a shoe on the support, a pair of sliding beds arranged to be moved toward and away from one another in the general direction transversely of the shoe, and a knife mounted upon each of the sliding beds and guided for reciprocation in the general direction lengthwise of the shoe, said knife being inclined to the heel-attaching face of the sole to form a heel-seat portion of the sole.

55. A heel-seat fitting machine having, in combination, a shoe support, a pair of crease plates constructed and arranged to enter the rand crease of a shoe on the support and having knife-guideways, a pair of sliding beds arranged to be moved toward and away from one another in the general direction transversely of the shoe, and a knife mounted upon each of the sliding beds and guided for reciprocation in the general direction lengthwise of the shoe, said knife being steeply inclined to the heel-attaching face of the sole and positioned in the knife-guideway during the heel-seat fitting operation.

56. A heel-seat fitting machine constructed and arranged to form a wide heel-seat having

its full thickness throughout substantially its entire width having, in combination, a shoe support, a pair of crease plates constructed and arranged to enter the rand 5 crease of a shoe on the support and having knife-guideways, a pair of sliding beds arranged to be moved toward and away from one another in the general direction transversely of the shoe, and a knife carried by 10 and guided for reciprocation in each of the sliding beds in the general direction lengthwise of the shoe, said knife being substantially inclined to the heel-attaching face of the sole and positioned in one of the knife- 15 guideways to trim the marginal portions of the sole to form a heel-seat portion of the sole while the sole is in an undistorted condition.

57. A heel-seat fitting machine having, in 20 combination, a jack for supporting a shoe, a pair of crease plates constructed and arranged to enter the rand crease of a shoe positioned on the jack, a pair of sliding beds arranged to be moved toward and away 25 from one another in the general direction transversely of the shoe, means for trimming the marginal portions of the sole of the shoe to shape a heel-seat portion of the sole, a shouldering knife mounted for reciprocation in each sliding bed in the general direction transversely of the length of the shoe, said knives being inclined to the heel-attaching face of the sole transversely of the sole, and means for actuating the knives relatively to the sliding beds and the jack. 30

58. A heel-seat fitting machine having, in combination, a jack for supporting a shoe, a pair of crease plates constructed and arranged to enter the rand creases of a shoe 40 positioned on the jack, a pair of sliding beds arranged to be moved toward and away from each other in the general direction transversely of the shoe, means for shaping a heel-seat, a shouldering knife carried by and 45 mounted for reciprocation in each sliding bed in the general direction transversely of the length of the shoe, said knives being inclined to the heel-attaching face of the sole transversely of the sole, means for operating the 50 knives relatively to the sliding beds and the jack, and means for initially setting the shouldering knives in their proper position relatively to the sliding beds.

59. A heel-seat fitting machine having, in 55 combination, a shoe support, a pair of sliding beds arranged to be moved toward and away from each other in the general direction transversely of the sole of a shoe on the support, a crease plate carried by each of the 60 sliding beds which plates are constructed and arranged to enter the rand crease of a shoe, a knife arranged to move substantially lengthwise of the shoe and carried by and 65 guided for reciprocation in each of the sliding beds, said knife being inclined to and

transversely of the sole of the shoe, a shouldering knife carried by each of the sliding beds and arranged to move transversely of the shoe, said knives being inclined to and transversely of the sole of the shoe, and means for reciprocating the knives relatively to the sliding beds and to the shoe support. 70

60. A heel-seat fitting machine having, in combination, a shoe support, a pair of sliding beds arranged to be moved toward and away 75 from one another transversely of the sole of a shoe on the support, a pair of crease plates each having a guideway, which plates are constructed and arranged to enter the rand crease of the shoe, a knife carried by and 80 guided for reciprocation in each of the sliding beds and being positioned in one of the guideways, a shouldering knife carried by each of the sliding beds and arranged to move transversely of the sole of the shoe, said shouldering knife being inclined to the sole transversely of the sole, and means for reciprocating the knives relatively to the sliding beds and to the shoe support. 85

61. A heel-seat fitting machine having, in 90 combination, a shoe support, a pair of sliding beds arranged to be moved toward and away from one another transversely of the sole of a shoe carried by the support, a pair of crease plates each having a guideway, which plates are constructed and arranged to enter the rand crease of the shoe, knives for 95 trimming the marginal portions of the sole to form a heel-seat portion of the sole carried by and guided for reciprocation in the sliding beds and positioned in the crease plate guideways, shouldering knives for forming heel breast receiving shoulders substantially at the heel breast line of the sole carried by the sliding beds and arranged to move transversely of the sole of the shoe, the shouldering knives entering the sole of the shoe at 100 places forward of that portion of the shoe engaged by said crease plates, and means for reciprocating the knives relatively to the sliding beds and to the shoe support. 105

62. A heel-seat fitting machine having, in combination, a shoe support, a pair of crease plates constructed and arranged to enter the rand crease of a shoe on the support and having guideways in their sole-engaging surfaces, said crease plates having depending portions arranged to contact with the sides of the shoe to limit the extent of the entrance of said crease plates in the rand crease, and means for trimming the sole to form a heel-seat portion of the sole, said trimming means being arranged to be positioned in the crease plate guideways. 115

63. A heel-seat fitting machine having, in 120 combination, a shoe support, crease plates constructed and arranged to enter the rand crease of a shoe on the support without distorting the sole, said crease plates having thin-finger portions arranged to enter the 125 130

rand crease without distorting the sole and having depending portions constructed and arranged for contact with the sides of the shoe upper to limit the entrance of the said fingered portions in the rand crease, and knives mounted for rectilinear movement in the general direction of the length of the shoe to trim the sole for forming a heel-seat portion thereof.

64. A heel-seat fitting machine having, in combination, a shoe support, a pair of crease plates constructed and arranged to enter the rand crease of a shoe on the support, said crease plates having depending portions which are arranged to contact with the shoe upper in order to limit the movement of the crease plates in the rand crease, a pair of knives arranged for movement in the general direction of the length of the shoe at a relatively steep inclination to and transversely of the heel-attaching surface of the sole of the shoe to trim the marginal portions of the sole, and a pair of shouldering knives mounted for reciprocation laterally of the shoe, said shouldering knives being inclined at an angle to and transversely of the sole of the shoe.

65. A heel-seat fitting machine having, in combination, a shoe support, a pair of crease plates constructed and arranged to enter the rand crease of a shoe carried by the support, said crease plates having depending portions which are constructed and arranged to contact with the shoe upper in order to limit the movement of the crease plates toward the shoe, a pair of reciprocating knives arranged to move in the general direction of the length of the shoe for trimming the marginal portions of the sole to form a heel-seat portion of the sole, and a pair of shouldering knives mounted for reciprocation laterally of the shoe for forming heel breast receiving shoulders substantially at the heel breast line of the sole.

66. A heel-seat fitting machine having, in combination, a shoe support, a pair of crease plates constructed and arranged to enter the rand crease of a shoe carried by the support, said crease plates having depending portions which are arranged to contact with the shoe upper in order to limit the movement of the crease plates in the rand crease, a pair of reciprocating beveling knives arranged to move in the general direction of the length of the shoe at a relatively steep inclination to and transversely of the heel-attaching surface of the sole of the shoe to trim the marginal portions of the sole to form a heel-seat portion of a sole, and a pair of shouldering knives mounted for reciprocation transversely of the sole of the shoe and arranged to move along the forward edge of the crease plates.

67. A heel-seat fitting machine having, in combination, a shoe support, crease plates constructed and arranged to enter the rand

crease of a shoe carried by the support, back gage mechanism for positioning the shoe to be trimmed lengthwise of the shoe relatively to the crease plates, a heel-engaging means for determining the position of the back gage, means for normally urging the back gage toward the shoe, means whereby the back gage is normally locked in its foremost position toward the shoe to prevent movement away from the shoe, and means controlled by the operator for unlocking the back gage to move the same from the shoe.

68. A heel-seat fitting machine having, in combination, a shoe support, crease plates constructed and arranged to enter the rand crease of a shoe carried by the support, a back gage mechanism for positioning the shoe to be trimmed lengthwise of the shoe relatively to the crease plates, a heel-engaging means for receiving a heel similar to the heel to be attached to the shoe and for determining the position of the back gage, means for urging said heel-engaging means against a heel, means whereby the heel is normally locked in the heel-engaging means and the back gage is normally locked to prevent its movement away from the shoe, and means controlled by the operator for unlocking the back gage to move the same away from the shoe and for releasing the heel from the heel-engaging means.

69. A heel-seat fitting machine having, in combination, a shoe support, crease plates constructed and arranged to enter the rand crease of a shoe on the support, back gage mechanism for positioning a shoe to be trimmed lengthwise of the shoe relatively to the crease plates, means whereby the back gage is normally urged toward the shoe and is normally locked to prevent movement away from the shoe, and means controlled by the operator for unlocking the back gage to move the same from the shoe.

70. A heel-seat fitting machine having, in combination, a shoe support, means for centering a shoe in the general direction of the width of the shoe, a back gage for positioning the shoe in the general direction of the length of the shoe, a heel-receiving gage for controlling the position of the back gage, said heel-receiving gage having abutments for contacting with the rear portion of the heel and the breast of the heel and having clamps constructed for movement with one of the aforesaid abutments and extending laterally of the heel and arranged centrally to position the heel with respect to the aforesaid abutments.

71. A heel-seat fitting machine having, in combination, a shoe support, means for centering a shoe in the general direction of the width of the shoe, a back gage for positioning the shoe in the general direction of the length of the shoe, a heel-receiving gage for controlling the position of the back gage, said heel-receiving gage having abutments

for contacting the rear portion of the heel and the breast of the heel and having clamps extending laterally of the heel and constructed and arranged to position the heel in its correct lateral position with respect to the aforesaid abutments, and means for operating the abutments and the clamps as a unit, said means comprising compensating means for permitting movement of the clamps toward the heel after the abutments have engaged the heel.

72. A heel-seat fitting machine having, in combination, a shoe support, crease plates constructed and arranged to enter the rand crease of a shoe upon the support for centering the shoe in the general direction of the width of the shoe, means to press the shoe thus positioned upon the support against the crease plates, a back gage for positioning the shoe in the general direction of the length of the shoe, a heel-receiving gage for controlling the position of the back gage, said heel-receiving gage having abutments for contacting the rear portion of the heel and the breast of the heel and having clamps extending laterally of the heel and constructed and arranged to position the heel in its correct lateral position with respect to the aforesaid abutments, means for locking the heel in the heel-receiving gage and for holding the back gage in its forward position, means whereby the back gage may be moved out of engagement with the shoe and the heel may be moved out of engagement with the heel-engaging means, and means to press the positioned shoe upon the support against the crease plates.

73. A heel-seat fitting machine having, in combination, a shoe support, means for centering a shoe in the general direction of the width of the shoe, a back gage for positioning the shoe in the direction of the length of the shoe, a heel-receiving gage for controlling the position of the back gage, said heel-receiving gage having abutments for contacting the rear portion of the heel and the breast of the heel and having clamps extending laterally of the heel and constructed and arranged to position the heel in its correct lateral position with respect to the aforesaid abutments, means for locking the heel in the heel-receiving gage and for holding the back gage in its forward position, means whereby the back gage may be moved out of engagement with the shoe and the heel may be moved out of engagement with the heel-engaging means, and means for adjusting the heel-engaging means for receiving heels of the different sizes.

74. A heel-seat fitting machine having, in combination, a shoe support, crease plates constructed and arranged to enter the rand crease of a shoe upon the support, a back gage arranged to contact with the rear portion of the shoe upper to position the shoe lengthwise

of the shoe for determining the length of the heel-seat to be trimmed, means for engaging a heel similar to the heel to be applied to the heel-seat of the shoe which is being trimmed, said means being constructed and arranged so as to place the back gage in such a position with respect to the shoe support that the length of the heel-seat must correspond to the length of the heel-attaching face which is engaged by the heel-engaging means, and means for locking the back gage and the heel-engaging means in their correct positions.

75. A heel-seat fitting machine having, in combination, a shoe support, crease plates constructed and arranged to enter the rand crease of a shoe on the support, a back gage to position the shoe on the machine lengthwise of the shoe, said support being arranged to be moved toward and away from the crease plates and comprising a work support post and a shoe supporting plate which is yieldingly movable in relation to the work support post, and means for actuating the shoe supporting plate to force the shoe against the crease plates and against the back gage.

76. A heel-seat fitting machine having, in combination, a shoe support, crease plates, a back gage and a clamp, which shoe support, crease plates, back gage and clamp function to position and support a shoe to be trimmed, said support being constructed and arranged to be moved toward and away from the crease plates and comprising a work support post, a shoe supporting plate which is yieldingly movable in relation to the work support post, means for positively actuating the shoe supporting plate to force the shoe against the crease plates and against the back gage, and means for actuating the clamp to engage the heel-attaching face of the sole of the shoe to be trimmed.

77. A heel-seat fitting machine having, in combination, means constructed and arranged to support a shoe having a sole attached thereto, and a pair of knives mounted for reciprocation substantially lengthwise of the supported shoe, each of the knives having a cutting edge extending transversely of the shoe and inclined at an angle to the heel-seat portion of the sole to bevel a lateral portion of the heel-seat portion of the sole.

78. A heel-seat fitting machine having, in combination, means to support a shoe having a sole attached thereto, means including a sliding bed mounted for movement toward and away from the shoe supporting means to cooperate with the same in positioning the shoe in the machine, and a knife having a cutting edge inclined at an angle to and extending transversely of the sole of the positioned shoe and mounted for movement relatively to the sliding bed in a direction lengthwise of the shoe to bevel a lateral portion of the heel-seat portion of the sole lengthwise thereof.

79. A heel-seat fitting machine having, in combination, means to support a shoe having a sole attached thereto, means including a sliding bed mounted for movement toward and away from the shoe supporting means to cooperate with the same in positioning the shoe in the machine, a knife having a cutting edge inclined at an angle to and extending transversely of the sole of the positioned shoe and mounted for movement relatively to the sliding bed in a direction lengthwise of the sole to bevel a lateral portion of the heel-seat portion of the sole lengthwise thereof, and a knife mounted for movement upon the sliding bed transversely of the sole to form a heel-breast receiving shoulder on the sole of the shoe.

80. A heel-seat fitting machine having, in combination, means constructed and arranged to support a shoe having a sole attached thereto, a sliding bed mounted for movement toward and away from said means, and a knife carried by the sliding bed and mounted for reciprocation relatively to said bed lengthwise of the shoe upon the shoe supporting means, said knife being constructed and arranged to bevel a lateral portion of the heel-seat portion of the sole of the shoe.

81. A heel-seat fitting machine having, in combination, means to support a shoe having a sole attached thereto, means including a sliding bed mounted for movement toward and away from the shoe supporting means to cooperate with the support to position the shoe in the machine, and a knife mounted for movement upon the sliding bed in a direction lengthwise of the positioned shoe to bevel the heel-seat portion of the sole of the shoe lengthwise thereof.

82. A heel-seat fitting machine having, in combination, means to support a shoe having a sole attached thereto, means including a sliding bed mounted for movement toward and away from the shoe supporting means to cooperate with the same in positioning the shoe in the machine and in retaining the shoe in said position, a knife movable with the sliding bed toward and away from the shoe and mounted for movement relatively to the sliding bed in a direction lengthwise of the shoe to bevel a lateral portion of the heel-seat portion of the sole lengthwise thereof, and a knife mounted for movement upon the sliding bed transversely of the sole to form a heel-breast-receiving shoulder in the sole of the shoe.

83. A heel-seat fitting machine having, in combination, means to position a shoe in a machine, and means to trim surplus material from the heel-seat portion of the sole, said sole positioning means including a crease plate having a guideway in its sole engaging surface to assist in directing the movement of the trimming means during the heel-seat fitting operation.

84. A heel-seat fitting machine having, in combination, means to support a shoe having a sole attached thereto, means to position the sole of the shoe in the machine, and means to trim surplus material from the heel-seat portion of the sole, said sole positioning means including a crease plate having a guideway in its sole engaging surface in which the trimming means is arranged to move and having a thin finger portion constructed and arranged to enter the rand crease of the shoe without substantially distorting the sole.

85. A heel-seat fitting machine having, in combination, a shoe support, a pair of knives mounted for reciprocation lengthwise and forwardly of a shoe carried by the support to form at the lateral portions of the heel-seat portion of its sole surfaces inclined to the heel-attaching face of the sole and extending lengthwise of the sole, and a pair of knives mounted for reciprocation transversely of the shoe substantially at the heel-breast line of the sole to form heel-breast receiving shoulders upon the sole of the shoe.

86. A heel-seat fitting machine having, in combination, a shoe support, crease plates constructed and arranged to enter the rand crease of a shoe upon the support, a pair of knives mounted for movement lengthwise and forwardly of the shoe simultaneously to trim the lateral marginal portions of the heel-seat portion of its sole while the sole is in a substantially undistorted condition, and means for forming heel-breast receiving shoulders on the sole.

87. A heel-seat fitting machine having, in combination, means comprising jaws one of which is mounted for movement relatively to the other constructed and arranged to enter the rand crease of a shoe at opposite sides of the shoe, and a cutter constructed and arranged positively to partake of the movement of the movable jaw and also mounted for movement relatively to said jaw, said jaw being constructed and arranged to support the sole in substantially undistorted condition against the pressure of the cutter and thus to cooperate with the cutter in forming a heel-breast receiving shoulder upon the sole while the sole is substantially undistorted.

88. A heel-seat fitting machine having, in combination, a pair of crease plates shaped and arranged to enter the rand crease of a shoe, a pair of cutters constructed and arranged for movement toward the plates, means constructed and arranged positively to move one of the plates together with one of the cutters toward the other plate and cutter, said crease plates being constructed and arranged to support the rear portion of the sole in undistorted condition against the pressure of the cutters and to cooperate with the cutters in forming heel-breast receiving shoulders upon the sole while the portion of

the sole being operated upon is undisturbed.

89. A heel-seat fitting machine having, in combination, relatively movable members constructed and arranged to be positioned between the heel-seat portion of the sole of a shoe and the overlasted margin of the counter portion of the shoe upper to which the sole is attached, and knives supported by the members and constructed and arranged positively to participate in said relative movement of the members and each mounted for movement relatively to its respective member, said members being constructed and arranged to support the heel-seat portion of the sole in undistorted condition against the pressure of their respective knives and to cooperate therewith to form heel-breast receiving shoulders at opposite sides of the sole while the heel-seat portion of the sole is substantially undistorted.

90. A heel-seat fitting machine having, in combination, means comprising jaws one of which is mounted for movement relatively to the other constructed and arranged to enter the rand crease of a shoe at opposite sides of the shoe, and a cutter carried by the movable jaw and also mounted for movement relatively to said jaw, said jaw being constructed and arranged to support the sole in substantially undistorted condition against the pressure of the cutter and to cooperate with the cutter in forming a heel-breast receiving shoulder upon the sole while the sole is substantially undistorted.

91. A heel-seat fitting machine having, in combination, jaws constructed and arranged to enter the rand crease of a shoe, means constructed and arranged to move the jaws thereby opening and closing the jaws, and cutters constructed and arranged for positive movement with the jaws during the opening and closing thereof and also constructed and arranged for movement relatively to the jaws, said jaws being constructed and arranged to support opposite sides of the sole in substantially undistorted condition against the severing pressure of the cutters and to cooperate with the cutters in forming a heel-breast receiving shoulders upon the sole while the sole is substantially undistorted.

92. A heel-seat fitting machine having, in combination, means comprising jaws one of which is mounted for movement relatively to the other constructed and arranged to enter the rand crease of a shoe at opposite sides of the shoe, and a cutter constructed and arranged to partake of the movement of the movable jaw and also mounted for movement relatively to said jaw, said jaw being constructed and arranged to support the sole in substantially undistorted condition against the pressure of the cutter and to constitute therewith a shear couple constructed and arranged to form a heel-breast receiving

shoulder upon the sole while the sole is substantially undistorted.

93. A machine for operating upon the attached sole of a shoe prior to the attaching of a heel to the shoe having, in combination, relatively movable crease plates constructed and arranged to be received in the rand crease of the shoe from the heel-breast line of the sole rearwardly of the shoe, knives relatively movable with the crease plates, and means for causing relative movement of the crease plates together with the knives, said knives being mounted for movement with reference to the crease plates and being constructed and arranged to cooperate with the crease plates to constitute shear couples for forming heel-breast-receiving shoulders upon the sole.

94. A heel-seat fitting machine having, in combination, jaws mounted for movement toward and away from each other in a single plane and constructed to enter the rand crease of a shoe, means constructed and arranged to open and to close the jaws, and cutters positively carried with the jaws during the opening and closing thereof and mounted also for movement toward and away from the jaws, said jaws being constructed and arranged to support opposite sides of the sole of the shoe in substantially undistorted condition against the severing pressure of the cutters as they move toward the jaws and to cooperate with the cutters in forming heel-breast receiving shoulders at opposite edge portions of the sole while the sole is substantially undistorted.

95. A heel-seat fitting machine having, in combination, means comprising a pair of plates shaped and arranged to enter the rand crease of a shoe, and a pair of cutters constructed and arranged for movement toward the plates, means for positively moving one of the plates together with one of the cutters toward the other plate and cutter, said crease plates being constructed and arranged to support the rear portion of the sole in substantially undistorted condition against the pressure of the cutters and to constitute with the cutters shear couples to form upon the undistorted sole heel-breast receiving shoulders located at opposite edge portions of the sole.

96. In a heel-seat fitting machine, a pair of crease plates constructed and arranged to enter the rand crease of a shoe prior to the attaching of a heel to the shoe, means for moving the crease plates relatively to each other, and a pair of knives carried by and also movable relatively to the crease plates, said knives being constructed and arranged to cooperate with portions of the crease plates to constitute shear couples for forming heel-breast-receiving shoulders upon the sole.

97. A machine for operating upon the at-

CERTIFICATE OF CORRECTION.

January 5, 1932.

Patent No. 1,840,030.

JOSEPH GOULDBOURN ET AL.

It is hereby certified that error appears in the printed specification of the above numbered patent requiring correction as follows: Page 10, line 12, claim 10, for the word "undisturbed" read undistorted; page 15, line 19, claim 47, for "guideways" read guideway; page 16, line 39, claim 58, for "creases" read crease, and page 18, line 82, claim 75, for "on" read in; and that the said Letters Patent should be read with these corrections therein that the same may conform to the record of the case in the Patent Office.

Signed and sealed this 12th day of July, A. D. 1932.

**M. J. Moore,
Acting Commissioner of Patents.**

(Seal)

heel-seat portion of the sole lengthwise thereof, and a pair of knives carried by and movable relatively to the plates, said knives being constructed and arranged to sever material partially trimmed from the sole by the first-named knives and also to form heel-breast-receiving shoulders upon the sole.

112. A heel-seat fitting machine having, in combination, supports, a plurality of crease plates one carried by each of the supports, said supports being mounted for movement toward and away from each other to move the crease plates into the rand crease of a shoe having a sole attached thereto, a plurality of drag knives one carried by each of the supports and constructed and arranged for movement with its support and also constructed and arranged for movement relatively to the support, said crease plates supporting the sole in substantially undistorted condition against the severing pressure of the cutters and constituting with the knives shear couples arranged to form heel-breast receiving shoulders at opposite sides of the sole.

113. A heel-seat fitting machine having, in combination, jaws mounted for movement toward and away from each other and constructed and arranged to enter the rand crease of a shoe, means for opening and closing the jaws, cutters constructed and arranged to be positively carried with the jaws during the opening and the closing of the same and mounted for movement transversely of a sole of a shoe engaged by said jaws, said jaws being constructed and arranged to support the opposite sides of the sole of the shoe in substantially undistorted condition against the severing pressure of the cutters and with the cutters to constitute shear couples constructed and arranged to form heel-breast receiving shoulders at opposite sides of the sole while the sole is substantially undistorted, and means for reducing the width of the heel-seat portion of the sole.

114. A heel-seat fitting machine having, in combination, a pair of beds, a crease plate carried by each of the beds, a knife mounted upon each of the beds, said beds being mounted for relative movement to bring the crease plates into engagement with the rand crease of a shoe having a sole attached thereto and prior to the attachment of the heel to the shoe for supporting the rear end of the sole, and means for determining the position of the sole lengthwise thereof relatively to the crease plates, each of the knives being mounted for movement relatively to its respective bed and being arranged to cooperate with its respective crease plate to constitute a shear couple constructed and arranged to form a heel-breast-receiving shoulder upon the sole.

115. A heel-seat fitting machine having, in combination, a pair of beds, a crease plate carried by each of the beds, a knife mounted

upon each of the beds, said beds being mounted for relative movement to bring the crease plates into engagement with the rand crease of the shoe having a sole attached thereto and prior to the attachment of the heel to the shoe for supporting the rear end of the sole, and means for determining the position of the sole lengthwise thereof relatively to the crease plates, each of the knives being mounted for movement transversely of the sole relatively to its respective bed and being arranged to co-operate with its respective crease plate to constitute a shear couple constructed and arranged to form a heel-breast-receiving shoulder upon the sole.

116. A heel-seat fitting machine having, in combination, means for supporting a shoe, and a pair of drag knives for operating upon the sole of the shoe carried by the support while the sole is in an undistorted condition and constructed and arranged simultaneously to trim the marginal portions of the heel-seat portion of the sole as they move forwardly of the sole.

117. A machine for operating upon the attached sole of a shoe prior to the attaching of a heel to the shoe having, in combination, a pair of crease plates constructed and arranged for positioning in the rand crease of the shoe to support the marginal portions of the sole from the heel breast line of the sole rearwardly, cutters constructed and arranged to form in the heel seat portion of the sole cuts extending lengthwise of the sole, and a pair of knives constructed and arranged to engage the forward edges of the crease plates and with the crease plates to constitute shear couples for forming transverse cuts in the sole at its heel breast line to cut heel breast receiving shoulders in the sole.

118. A heel seat fitting machine having, in combination, a pair of supports, a plurality of crease plates one carried by each of the supports, one of the supports being mounted for rectilinear movement toward and away from the other to cause the crease plates to enter the rand crease of a shoe, cutting mechanism constructed and arranged to reduce the rear portion of the sole of the shoe widthwise to form a reduced heel seat portion thereof, a pair of knives each mounted for movement relatively to its respective crease plate, said crease plates being constructed and arranged to support the sole in substantially undistorted condition against the severing pressure of the knives and to constitute therewith shear couples constructed and arranged to form heel breast receiving shoulders upon the sole while the sole is substantially undistorted.

119. A heel seat fitting machine having, in combination, a pair of beds each comprising a crease plate, said beds being mounted for relative movement to bring the crease plates into engagement with the rand crease of a shoe

having a sole attached thereto prior to the attachment of the heel to the shoe for supporting the rear portion of the sole, cutters supported by the beds and constructed and arranged to reduce the heel seat portion of the sole widthwise, cutters mounted for relative movement with the beds, said second-named cutters being mounted for movement relatively to their respective crease plates and being constructed and arranged to cooperate therewith to constitute shear couples for forming heel breast receiving shoulders upon the sole.

120. A heel seat fitting machine having, in combination, a pair of beds each of which comprises a crease plate, said beds being mounted for relative movement to bring the crease plates into engagement with the rand crease of a shoe having a sole attached thereto prior to the attachment of a heel to the shoe to support the rear portion of the sole, a cutting blade supported by each of the beds, said cutting blades being mounted for relative movement with the beds and each being mounted for movement relatively to its respective crease plate to form a heel seat portion thereof of reduced width, cutters relatively movable with the beds, mechanism constructed and arranged to cause relative movement of the beds, said last-named cutters being mounted for movement relatively to the beds and being constructed and arranged to cooperate with the crease plates of said beds to constitute shear couples for forming upon the sole heel breast receiving shoulders extending from the lateral edges of the sole to the reduced heel seat portion thereof.

In testimony whereof we have signed our names to this specification.
